INSECTICIDE, FUNGICIDE, AND THE LIKE

Henricus Jacobus Charles Tendeloo, The Hague, Netherlands, assignor to Shell Development Company, San Francisco, Calif., a corporation of Delaware

No Drawing. Application March 26, 1937, Serial No. 133,185. In the Netherlands April 20, 1936

8 Claims. (Cl. 167—33)

This invention relates to materials useful for destroying vermin and other noxious organisms and deals with a new class of compounds which are particularly advantageous for such uses.

One object of the invention is to provide a material which is convenient to ship, store and handle and which can be effectively used for insecticidal, fungicidal and bactericidal purposes.

I have found that sulfides containing at least one sulfur atom attached to two carbon atoms which are joined in a saturated carbon chain, and especially those having a sulfur atom attached to two directly connected carbon atoms e. g. sulfides containing the group

are particularly effective for the said purposes. Sulfides of this type may be derived from either unsaturated aliphatic or alicyclic hydrocarbons and not only may the sulfides themselves be used but also suitable derivatives thereof.

Typical sulfides which may be used in accordance with my invention include, for example, alkyl sulfides, such as ethylene sulfide

30 α propylene sulfide

symmetrical dimethyl ethylene sulfide

isobutylene sulfide

α butylene sulfide

α amylyne sulfide

symmetrical methyl ethyl ethylene sulfide

isopropyl ethylene sulfide

trimethyl ethylene sulfide

tetramethyl ethylene sulfide

trimethylvlene sulfide

and homologous saturated aliphatic sulfides, as well as the similar unsaturated aliphatic sulfides such as butadiene monosulfide

isoprene monosulfide

and the like, and the corresponding polysulfides as butadiene disulfide

etc. Also suitable are the analogous sulfides of cyclic compounds including both aliphatic and aromatic compounds, such, for example, as cyclohexene sulfide

styrene sulfide

and the like. Sulfides containing substituents

such as halogen, —NH₂, —OH, —COOH, —CN, —AsH₂, etc., as oxypropylene sulfide

5

monochlor ethylene sulfide

S

10 and the like, may be used in place of, or admixed with, the unsubstituted sulfide or sulfides chosen.

These sulfides may be applied as the chemical individuals or as mixtures thereof or as crude materials containing other compounds which may 15 or may not have a similar action under the conditions of application, such, for example, as the mixtures of sulfides and dithiocyanates obtainable as crude products in one method of manufacturing the sulfides. Other substances, which 20 may act solely as diluents or carriers, such as hydrocarbons, kieselguhr, etc., or which may possess desirable insecticidal, fungicidal or bactericidal properties, as HCN, CS₂, epoxyethane or the like, may be added to the sulfide or sulfides 25 chosen, either before or at the time of application.

In general, the sulfides used in my insecticidal preparations, may be manufactured by reaction of suitable dithiocyanates with a solution of 30 Na₂S containing NaHS, a process described, for example, by Delépine in the Bull. Soc. Chim. (4) 27, 740 (1920). It has been found desirable to avoid as much as possible any substantial rise in temperature during the process, and not as generally recommended in the literature, to separate the product from the reaction mixture by distillation with steam, but to isolate it from the reaction mixture by means of vacuum distillation at a low temperature. As the before mentioned 35 sulfides, especially the lower sulfides are somewhat unstable, they are preferably used together with suitable amounts of stabilizing agents such as phenols, etc.

The lower molecular sulfides are in general 40 volatile substances which evaporate readily and have been found to be eminently suitable for use as so-called gassing insecticides. As such they may be effectively used in destroying insects in food stuffs and in fumigating warehouses, dwellings and ships as well as for the destruction of vermin on human beings and animals. The higher molecular sulfides are less volatile and may, therefore, be more suitably used as contacting or stomachal insecticides, e. g. for combating plant lice and in orchard sprays, etc., for protection against aphids, scale, etc.

For the purpose of making my invention more clear it will be further described with more particular reference to the use of ethylene sulfide 60 and butylene sulfides. It will be understood that this implies no limitation on my invention, however, as the other sulfides already referred to are also effective in similar and other suitable applications.

65 Because of its low boiling point (55° C.) and its exceptional activity ethylene sulfide is especially useful for insecticidal and analogous purposes. Its activity is such that it may be used effectively at low concentrations which lie outside the explosive limits. For this reason it makes a desirable substitute for carbon disulfide fumigants and can in fact be safely employed where the fire hazard of the latter makes it too dangerous to use. In comparative tests on cockroaches, 70 ethylene sulfide was found to be about twenty

times as effective as ethylene oxide. In a representative test ethylene sulfide was introduced into a closed volume of air to a concentration of only 0.1%. At this low concentration the cockroaches died within 24 hours.

Substantially corresponding results were obtained with butylene sulfides, paralysis and death of cockroaches seeming to occur even somewhat more rapidly although this is not fully established. The following table, in which 10 L=living, P=paralyzed and D=dead, shows the results obtainable.

Concentration of butylene sulfide as gas in air (percent by volume)	Condition of the cockroaches after—												15	
	1 hour			2 hours			3 hours			24 hours				
	L	P	D	L	P	D	L	P	D	L	P	D		
0.	5	—	—	5	—	—	5	—	—	5	—	—	5	
0.1.	2	3	—	1	4	—	5	—	—	5	—	—	5	
0.5.	1	4	—	5	—	—	5	—	—	5	—	—	5	
1.0.	4	1	—	3	2	—	5	—	—	5	—	—	5	
2.0.	3	2	—	2	3	—	5	—	—	5	—	—	5	

20 My invention is not only capable of wide variation with respect to the type of organic sulfide having a sulfur atom attached to two carbon atoms joined in a saturated carbon chain, which may be used, but also with respect to the 30 character of organisms which may be controlled therewith, as these also include flies, gnats, mosquitoes, weevils, beetles and the like. It will therefore be clear that my invention is not to be regarded as limited to the details of operation 35 described, but only by the terms of the accompanying claims, in which it is my intention to claim all novelty inherent therein as broadly as is possible in view of the prior art.

25 I claim as my invention:

1. As an insecticide, fungicide, bactericide and the like, a preparation containing as an active ingredient an organic sulfide having at least one sulfur atom attached to two directly connected carbon atoms.

2. As an insecticide, fungicide, bactericide and the like, a preparation containing as an active ingredient an aliphatic monomeric organic sulfide having a sulfur atom attached to two directly connected carbon atoms which are joined 50 in a saturated carbon chain.

3. An insecticide composition containing an effective amount of an alkyl sulfide having a sulfur atom attached to two directly connected saturated carbon atoms.

4. An insecticide containing as an active ingredient an unsaturated aliphatic sulfide having a sulfur atom attached to two directly connected saturated carbon atoms.

5. An insecticide containing as an active ingredient a carbocyclic sulfide having a sulfur atom attached to two directly connected saturated carbon atoms.

6. A fumigant comprising an effective amount of ethylene sulfide.

7. A fumigant comprising an effective amount of a butylene sulfide.

8. As an insecticide, fungicide, bactericide and the like, a preparation containing as an active ingredient an aliphatic monomeric organic sulfide having a sulfur atom attached to two carbon atoms which are joined in a saturated carbon chain through an ethylene radical.

HENRICUS JACOBUS

CHARLES TENDELOO.
